United States Patent Office

Des. 219,558
Patented Dec. 22, 1970

219,558

ELECTRIC FISHING MOTOR CONTROL HEAD
Harold D. Fetty, Detroit, Mich., assignor to Osborn
Engineering Corporation, a corporation of Delaware

Filed Oct. 23, 1969, Ser. No. 19,688

Term of patent 14 years

Int. Cl. D12—99

U.S. Cl. D71—1

FIG.1

FIG.2

FIG.3

FIG.4

FIG.5

FIG. 1 is a perspective view of the electric fishing motor control head;

FIG. 2 is a top view;

FIG. 3 is a side view;

FIG. 4 is a front view; and

FIG. 5 is a rear view.

The broken lines are for illustrative purposes only.

I claim:

The ornamental design for an electric fishing motor control head, substantially as shown and described.
